(57) **CLAIM**

The ornamental design for LED package, as shown and described.

DESCRIPTION

FIG. 1 is a perspective view of another embodiment of an LED package showing our design;

FIG. 2 is a top plan view of the LED package shown in FIG. 1;

FIG. 3 is a bottom plan view of the LED package shown in FIG. 1;

FIG. 4 is a front elevation view of the LED package shown in FIG. 1, with the back elevation view being substantially similar;

FIG. 5 is a side elevation view of the LED package shown in FIG. 1, with the opposite side elevation view being substantially similar;

FIG. 6 is a bottom perspective view of the LED package shown in FIG. 1;

FIG. 7 is a perspective view of another embodiment of an LED package showing our design;

FIG. 8 is a top plan view of the LED package shown in FIG. 7;

FIG. 9 is a bottom plan view of the LED package shown in FIG. 7;

FIG. 10 is a front elevation view of the LED package shown in FIG. 7, with the back elevation view being substantially similar;

FIG. 11 is a side elevation view of the LED package shown in FIG. 7, with the opposite side elevation view being substantially similar;

FIG. 12 is a bottom perspective view of the LED package shown in FIG. 7;

FIG. 13 is a perspective view of another embodiment of an LED package showing our design;

FIG. 14 is a bottom perspective view of the LED package shown in FIG. 13;

FIG. 15 is a top plan view of one component of the LED package shown in FIG. 13; and,

FIG. 16 is a bottom plan view of one component of the LED package shown in FIG. 13.

Any broken lines in FIGS. 1-16 are for illustrative purposes only and form no part of the claimed design.
